UNITED STATES PATENT OFFICE.

ROBERT D. PIKE, OF SAN FRANCISCO, CALIFORNIA, ASSIGNOR TO CHARLES W. PIKE, OF SAN FRANCISCO, CALIFORNIA.

DESIGN FOR A DISPLAY-HOLDER.

53,604.

Specification for Design.

Patented July 15, 1919.

Application filed April 17, 1919. Serial No. 290,872. Term of patent 14 years.

To all whom it may concern:

Be it known that I, ROBERT D. PIKE, a citizen of the United States, residing at the city and county of San Francisco, State of California, have invented a new, original, and ornamental Design for Display-Holders, of which the following is a specification, reference being had to the accompanying drawing, forming part thereof, wherein—

Figure 1 is a perspective view of a display holder showing my new design.

Fig. 2 is a front elevation thereof.

I claim:—

The ornamental design for a display holder, as shown.

In witness whereof I have signed my name to this specification in the presence of two witnesses.

ROBERT D. PIKE.
